(57) **CLAIM**

The ornamental design for a combined pneumatic vehicle jack and compressor, as shown and described.

DESCRIPTION

FIG. 1 is a front elevation view of a combined pneumatic vehicle jack and compressor showing my new design with the pneumatic vehicle jack, the compressor, and an adaptor separated for clarity;

FIG. 2 is a rear elevation view thereof;

FIG. 3 is a right elevation view thereof;

FIG. 4 is a left elevation view thereof;

FIG. 5 is a top plan view thereof;

FIG. 6 is a bottom plan view thereof; and,

FIG. 7 is an isometric view thereof.

1 Claim, 6 Drawing Sheets

FIG. 1

FIG. 4
